UNITED STATES PATENT OFFICE.

RUDOLF HARTWIG, OF ESSEN, GERMANY, ASSIGNOR TO FRIED. KRUPP AKTIEN-
GESELLSCHAFT, OF ESSEN-ON-THE-RUHR, GERMANY.

ARRANGEMENT OF TRACK FOR RAILWAY-GUNS.

1,361,460.

Specification of Letters Patent.

Patented Dec. 7, 1920.

Application filed September 4, 1920. Serial No. 408,401.

To all whom it may concern:

Be it known that I, RUDOLF HARTWIG, residing at Essen, Germany, a citizen of the German Republic, have invented a certain 5 new and useful Improvement in Arrangement of Track for Railway-Guns, of which the following is a specification.

This invention relates to that type of arrangement of railway track for railway 10 guns, which enables the traverse to be taken by running the gun over the track. The object of the invention is to provide an arrangement of railway track of this kind, which affords a field of traverse up to 360°, 15 while at the same time it takes up but little space and guarantees great stability of the gun when it is fired.

The invention will be described with reference to the accompanying drawings which 20 diagrammatically illustrate the invention.

Figures 1 and 2 show a plan view of a construction of the arrangement of railway track together with the gun in different positions and

25 Figs. 3 and 4 are similar views of a second construction of the invention.

Referring to Figs. 1 and 2 the arrangement of railway track is in the form of a junction, the two sections of rails of which 30 are denoted by A and A¹, which sections are connected with the track A², which leads to the junction by a set of points, a turntable or the like. The gun, which is intended to be used on this junction is provided with a 35 railway gun carriage, the frame B of which carries the gun barrel B³ and is supported on two bogies B¹ B². When running the gun into the junction the rear bogie B², for example, is first run onto the track A¹ and then the front bogie B¹ is run on to the track A, which causes a mutual rocking of the frame B and of the bogies B¹ B² about the axes b⁴ b⁵. By running the bogies on to the tracks A and A¹, the gun can be brought 45 from the position shown in dotted lines in Fig. 1 through the positions indicated by dot and dash lines into the position indicated by full lines in Fig. 1. In all the intermediate positions the barrel B³ of the

gun points toward the left in an upward 50 direction in the drawings. Fig. 2 shows how the gun barrel B³ is pointed toward the right in an upward direction when the bogies B¹ B² are in a different mutual position on the tracks A and A¹. If on the contrary the front bogie B¹ be run on to the track A¹ and the rear bogie B² on to the track A, the gun barrel B³ will point downward (in the drawings). 55

By running the gun around the junction 60 therefore, a field of traverse up to 360° can be obtained, as a rule however only a comparatively small angle of this field of traverse will be made use of. The junction is so laid out that the firing positions likely 65 to be required are situated in the vicinity of the reversed position of the gun. This insures the advantage that at least one of the bogies describes a comparatively large angle with the direction of fire (see the reversed 70 position indicated by full lines in Figs. 1 and 2, in which the bogie B² is at right angles to the direction of fire and the bogie B¹ likewise at a comparatively large angle thereto). In consequence of this the rail- 75 way gun carriage does not run back when the gun is fired, so that it is not necessary to run the gun out into the firing position again after each shot. The above described arrangement of track is further distin- 80 guished by the fact that it takes up far less space than the sections of railway with large radii of curvature hitherto used for the same purpose and in which the bogies of the gun run on one and the same line of 85 rails.

The arrangement of track shown in Figs. 3 and 4 is constructed as a triangular junction with three sides C, C¹, C² and approach lines C³, C⁴, C⁵. The parts of the gun con- 90 cerned are denoted as in Fig. 1 by B, B¹, B², B³. The method of using this arrangement of railway track can be clearly understood with reference to the drawings and therefore needs no further description. 95

Claims:

1. The method of training a railway gun provided with two sets of bogies upon a

railway track junction formed with diverging lines of rails which consists of running the sets of bogies over different lines of the rails.

5 2. The method of training a railway gun provided with two sets of bogies upon a railway track junction which consists of moving the sets of bogies to different posi-

tions on the lines of rails of the track junction.

The foregoing specification signed at Es-
sen, Germany, this 11th day of June, 1920.

RUDOLF HARTWIG.

In presence of—

HANS GOTTSMANN,
JOSEF OLBERTZ.
